UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

MULTIJET CONDENSER.

Application filed March 15, 1923. Serial No. 625,416.

To all whom it may concern:

Be it known that I, PAUL A. BANCEL, a citizen of the United States, and a resident of Nutley, county of Essex and State of New

5 Jersey, have invented a certain Multijet Condenser, of which the following is a specification, accompanied by drawings.

This invention relates to low level multi-jet condensers, and one object of the invention is to enable air and gases to be conveniently withdrawn from the condenser especially in the case of excessive air leakage, thus avoiding the necessity of using larger amounts of water.

15 Another object of the invention is to permit the withdrawing of air and gases from the condenser while at the same time protecting the vacuum pump and preventing water and steam from entering the air withdrawal chamber and passing to the vacuum pump.

20 Further objects of the invention will hereinafter appear, and the invention is shown in its preferred forms in the accompanying drawings, in which—

25 Figure 1 is a longitudinal sectional elevation of a condenser embodying the invention, and

30 Figure 2 is a similar view of a modification.

Referring to the drawings, the condenser casing comprises the lower section or body A and the upper section or head B suitably secured together. Within the head is provided a nozzle plate C having a plurality of nozzles D adapted to emit convergent jets or streams of water directed to the discharge opening E of the casing in the usual manner. The nozzle plate C is carried in a water head F and water enters at the inlet G.

35 A diffuser or Venturi tube H is shown connected to the lower section or body A of the casing, and a tail pipe J is partially submerged within the water K within the tank or sump L, which is provided with a weir O and over-flow outlet P. A weighted flap valve Q is connected to the lower end of the tail pipe J.

40 The discharge opening E, which is in this instance formed on the diffuser H, is preferably provided with a liner R of suitable metal, as brass. A suitable vacuum breaker S is connected to the condenser casing and controlled by a ball T, and a by-pass U connects the vacuum breaker with the interior of

the head B of the condenser. The head B is also provided with a man hole cover V and the steam inlet W is located at the top of the condenser casing.

45 In the form of the invention shown, the convergent jets of water are unprotected, so that the steam enters the condenser from above and passes into direct and immediate contact with the jets, without the interposition of a combining tube, vanes or other guiding means, substantially as shown in my co-pending application, Serial No. 625,415 filed March 15, 1923.

50 In accordance with this invention, a protective apron X supported from the condenser casing independently of the mounting for the nozzles D is located in the lower portion of the chamber within the condenser casing around the discharge opening E, thus forming an air chamber Y between the apron and the walls of the condenser casing. This air chamber is located wholly above the discharge opening into the diffuser. The walls of the apron X preferably diverge or flare away from the discharge opening E and apertures or spaces Z are provided at the lower portion of the apron, adjacent the discharge opening, for the passage of air and gases into the air chamber Y. Means are provided 55 for withdrawing air from the chamber Y and as shown, a withdrawal pipe a is connected to the casing and communicates with the aperture b leading to the air chamber. Any suitable form of pump, as a vacuum pump (not shown) withdraws air from the chamber.

60 The apron X prevents water and steam from passing into the air chamber and from thence into the pump, but air and gases may enter the air chamber through the apertures or openings Z in the lower portion of the apron and be withdrawn by the air pump through the aperture b.

65 In the modification shown in Figure 2, the apron c is of substantially the same type as that indicated in Figure 1, except that the perforations d extend in several rows through a portion of the apron.

I claim:

70 In a low level multi-jet condenser, the combination of a condenser casing, a nozzle plate having nozzles mounted thereon adapted to emit a plurality of unprotected convergent streams of water through the cham-

105

110

ber formed by said casing, a discharge opening at the lower end of said casing, a diffuser having a contracted throat to which the streams of water are directed, a tank, and a tail piece on the diffuser extending into the tank, an inlet to said chamber for the introduction of steam, a perforated protective apron in the lower portion of the chamber around the discharge opening forming an air chamber between the apron and the walls of the condenser casing, said

apron being supported from the condenser casing independently from the mounting for the said nozzles, said air chamber being located wholly above the discharge opening ¹⁵ into the diffuser, and means for withdrawing leakage air and gases from said air chamber beneath said apron.

In testimony whereof I have signed this specification.

PAUL A. BANCEL.
